BOW FORMING APPARATUS

Ralph K. Reynolds, Danbury, Conn., assignor to
 The Mallory Hat Company, Danbury, Conn., a
 corporation of Connecticut

Application July 18, 1933, Serial No. 680,936

15 Claims. (Cl. 223—46)

This invention relates to a bow forming device.

One of the objects of this invention is to provide a bow forming device which will be simple, 5 practical, and thoroughly durable. Another object is to provide a device of the above character which will aid materially in the formation of a bow by simplifying the various necessary steps incidental thereto. Another object is to provide 10 a device of the above character which, because of its utility and practicability, will materially speed the production of bows or the like. Another object is to provide a device of the above character which will standardize the construction 15 and formation of bows or the like to create a uniform high quality. Another object is to provide a device of the above character which will permit the formation of bows by unskilled and cheap labor. Other objects will be in part obvious and in part pointed out hereinafter.

The invention accordingly consists in the features of construction, combinations of elements, and arrangements of parts, all as will be illustratively described herein, and the scope of the 25 application of which will be indicated in the following claims.

In the accompanying drawings, in which is shown one of the various possible embodiments of my invention,

30 Figure 1 is a top plan view of my device for forming bows or the like;

Figure 2 is a longitudinal side elevation of the device shown in Figure 1;

Figure 3 is a vertical sectional view, taken along 35 the line 3—3 of Figure 2;

Figure 4 is a top plan view of the device shown in Figure 1;

Figure 5 is a view substantially similar to Figure 4;

40 Figure 6 is a view substantially similar to Figures 4 and 5, and

Figure 7 is a side elevation of the article.

Similar reference characters refer to similar parts throughout the several views of the drawings.

As conducive to a clearer understanding of certain features of this invention, it might here be pointed out that the formation of ribbon bows for hat bands or the like has been accompanied 50 by considerable difficulty and inconvenience, as, for example, the attempt to produce a uniform article by hand. In the past, these bows have been made by groups of skilled workers purely by hand with the result that inferior bows were often turned out and such bows were not of uni-

form quality due to the peculiar characteristics of each individual worker. Furthermore, the formation of such bows by hand takes a good deal of time and requires a skilled worker; the result of this condition is an undue expense in production coupled with an article often inferior in many respects. One of the objects of this invention is to provide a device for overcoming the above-mentioned difficulties as well as many others.

Referring now to the drawings in detail, there is shown in Figure 2 a base member 10 preferably formed from wood or the like and supporting a plate 11 on its top side. Plate 11 is preferably secured to base 10 by way of suitable wood screws 15 12 and 13 extending through the plate and into base 10, as best shown in Figure 1.

Plate 11 is of suitable dimensions to support a ribbon to be formed into a bow for hat bands or the like, as will be more fully described herein- 20 after. Formed in plate 11 is a channel 14 extending thereacross substantially at right angles to the longitudinal axis of said plate member. As best shown in Figure 2, wall 15 of channel 14 is preferably squared or at right angles to the plane of the top surface of plate 11 while wall 16 thereof is beveled or oblique to this plane. Accordingly when a strip of material is to be removed from channel 14, in a manner to be described more fully hereinafter, it may be easily slipped to the right, as viewed in Figure 2, over the beveled surface of wall 16.

In the vicinity of one end of plate 11 (the left-hand end as viewed in Figure 1) there is a square generally indicated at 17 extending above the top surface of the plate. Thus square 17 comprises a wall 18 substantially parallel to channel 14 and a wall 19 one edge of which is in substantial alinement with one edge 20 of the plate. Wall 19, furthermore, is beveled at its end portion 19a, the bevel extending from the outer side of the wall toward the inner side thereof or toward a plane passing through edge 20 and at right angles to plate 11.

The ends of a pair of resilient parts 21 and 22 are secured to plate 11 at points substantially adjacent square 17 preferably by way of rivets generally indicated at 23. As more clearly shown in Figure 2, parts 21 and 22 extend over channel 14 and engage the top surface of plate 11 on the far side of the channel or on the right-hand side thereof, as viewed in the drawings. Also, I prefer to turn up the ends of parts 21 and 22 in the manner of end portion 22a, best shown in Figure 2.

I have now provided a practical device which may be used with a great deal of success in increasing the efficiency and speed of production of bows for hat bands or the like. Not only may 5 such bows be manufactured more rapidly with this device, but, also, a more uniform product results therefrom.

I first take a strip of ribbon of suitable length and fold it along its longitudinal length to form 10 a double thickness of ribbon as indicated at 24 in Figure 4. Preferably ribbon 24 is so folded that one edge portion 24a overlaps the other edge portion 24b. Next, ribbon 24 in its folded position is placed upon plate 11 adjacent the 15 ends of parts 21 and 22 and slipped along the plate under the parts toward channel 14. Finally ribbon 24 reaches the position shown in Figure 4 so that its folded edge rests squarely against the squared wall 15 of channel 14 and 20 preferably so that edge 24a is above edge 24b. It will be noted that when ribbon 24 is in this position, it is of sufficient length so that its opposite ends extend beyond the opposite longitudinal edges of plate 11.

25 I now take a suitable length of ribbon 27 which is to form the main body portion of the bow and substantially at its intermediate portion I secure a piece of relatively stiff material 25, for example, by way of stitches generally indicated 30 at 26 (see Figure 5). This length of ribbon may now be folded back upon itself so that it forms a double thickness, with strip 25 adjacent the folded edge. Preferably when in this position, the end 27a overlaps the end 27b, all as more 35 clearly shown in Figure 5. Ribbon 27 is now placed upon plate 11 over parts 21 and 22, as best shown in Figure 5, so that the folded edge thereof rests against wall 18 of square 17 and one longitudinal edge thereof is in engagement with 40 wall 19 of the square. When in this position, ribbon 27 is squared off on the top of plate 11 so that its edges are substantially parallel to the edges of plate 11, and it will be noted that ribbon 24 extends across the plate under ribbon 27 so that its free ends project beyond the 45 opposite sides thereof. When ribbon 27 is being placed in the position shown in Figure 5, it is gradually moved toward squared portion 17 and it will be noted that when the upper left-hand 50 corner thereof, as viewed in the drawings, engages wall 19, the beveled portion 19a thereof serves to guide the corner toward the inner surface of wall 19. It is also to be noted that when ribbon 27 is in its final position, as shown in 55 Figure 5, end 27a thereof preferably overlaps end 27b.

End 24c of ribbon 24, as viewed in Figure 5, is now brought over the edge of ribbon 27 so that ribbon 24 bunches ribbon 27. I now bring end 60 24d of ribbon 24 down upon ribbon 27 to further bunch ribbon 27 and form a substantially longitudinal fold 28 in ribbon 27, this fold preferably overlapping end 24c of ribbon 24. A strip 65 29 of adhesive material is now placed upon ends 24c and 24d of ribbon 24 to hold them permanently in the position shown in Figure 6. The article may now be removed from my device and it will be noted that upon sliding the article to the right, as viewed in Figure 4, strip 70 24 may easily slide over the beveled surface of wall 16 even though compressed within channel 24 by resilient parts 21 and 22.

The ribbons 24 and 27 have now formed a completed bow, generally indicated at 30 in Figure 7, and it will be noted that this bow is neat in

appearance and ready for immediate application to the band of a hat. For example, if a band has already been secured to the crown portion of the hat, bow 30 may be sewed in a desirable position thereon by a very few stitches, 5 as, for example, stitches in the vicinity of each corner of ribbon 27 and preferably a few stitches on each side of ribbon 24.

It will be noted that the number of steps necessary to form a bow when using my device is 10 comparatively few in comparison to the steps necessary in the formation of a hand-made bow. It is often considered desirable to have a bunch near the central portion of such a bow and it will be seen that I can form such a bunch in a 15 very easy manner with the help of my forming device. All of these factors are material advantages in the production of this important portion of the usual hat.

It will thus be seen that I have provided a 20 thoroughly practical device for forming bows or the like for hat bands in which the several objects hereinabove mentioned, as well as many others, are successfully accomplished.

As many possible embodiments may be made 25 of the mechanical features of the above invention and as the embodiment herein described might be varied in various parts, all without departing from the scope of the invention, it is to 30 be understood that all matter hereinabove set forth or shown in the accompanying drawings is to be interpreted as illustrative and not in a limiting sense.

I claim:

1. In bow forming apparatus, in combination, 35 a support having a flat top surface, means rising above said top surface and forming a squared abutment near one end of said support, and spring means adapted to hold a piece of ribbon flat on said top surface, said support having a 40 channel formed in said top surface extending crosswise thereof and intermediate the ends of said spring means.

2. In bow forming apparatus, in combination, 45 a wooden base member, a metal plate secured to said base member and having a channel extending thereacross substantially at right angles to its longitudinal sides, one side of said channel having a substantially beveled edge and the other side of said channel having a straight edge, a 50 wall member extending across said plate substantially at right angles to said channel and near one end of said plate, a wall member extending along a portion of one edge of said plate substantially at right angles to said last-mentioned wall member, said wall members forming a squared abutment, and a pair of spring members secured to said plate substantially adjacent said wall members and having portions extending along the top of said channel, the ends of said spring 55 members extending upwardly.

3. In bow forming apparatus, in combination, 60 a wooden base member, a metal plate secured to said base member and having a channel extending thereacross substantially at right angles to its longitudinal sides, one side of said channel having a substantially beveled edge and the other side of said channel having a straight edge, a 65 wall member extending across said plate substantially at right angles to said channel and near one end of said plate, a wall member extending along a portion of one edge of said plate substantially at right angles to said last-mentioned wall member, said wall members forming a squared abutment, and a pair of spring members 70

- secured to said plate substantially adjacent said wall members and having portions extending along the top of said channel.
4. In bow forming apparatus, in combination, 5 a wooden base member, a metal plate secured to said base member and having a channel extending thereacross substantially at right angles to its longitudinal sides, a wall member extending across said plate substantially at right angles to 10 said channel and near one end of said plate, a wall member extending along a portion of one edge of said plate substantially at right angles to said last-mentioned wall member, said wall members forming a squared abutment, and a pair 15 of spring members secured to said plate substantially adjacent said wall members and having portions extending along the top of said channel, the ends of said spring members extending upwardly.
- 20 5. In bow forming apparatus, in combination, a base member having a channel extending thereacross, a wall extending above the top surface of said base member and substantially adjacent one end of said base member spaced from said channel, said wall being substantially parallel to said channel, and spring means secured to said base member and having free portions extending along the top of said base member over said channel.
6. In bow forming apparatus, in combination, 30 a base member having a channel extending thereacross, a wall extending above the top surface of said base member and substantially adjacent one end of said base member spaced from said channel, said wall being substantially parallel to said channel, spring means secured to said base member and having free portions extending along the top of said base member over said channel, and means extending along a portion of one longitudinal side of said member above the top surface 40 thereof adjacent said wall.
7. In bow forming apparatus, in combination, a base member for supporting a double thickness of ribbon to be formed into a bow and having a channel formed therein running substantially at 45 right angles to the longitudinal length of said base member, and a pair of resilient strips secured to said base member having their free ends extending over said channel to hold a second strip of material in said channel under said first- 50 mentioned strip.
8. In bow forming apparatus, in combination, a base member for supporting a double thickness of ribbon to be formed into a bow and having a channel formed therein running substantially at 55 right angles to the longitudinal length of said base member, a pair of resilient strips secured to said base member having their free ends extending over said channel to hold a second strip of material in said channel under said first- 60 mentioned strip, and a square secured to said base member near one end thereof so that the end of said first-mentioned strip may abut thereagainst.
9. In bow forming apparatus, in combination, 65 a metal base member having a channel extending across its top surface, one side of said channel being substantially beveled and the other side being squared, and a resilient strip secured to said base member at one end and having its free end overlapping said channel.
10. In bow forming apparatus, in combination, a metal base member having a channel extending across its top surface, one side of said channel being substantially beveled and the other side being squared, a resilient strip secured to said base member at one end and having its free end overlapping said channel, and a right angle part secured to said base member and extending above the top surface thereof, said right angle part being spaced from said channel. 10
11. In bow forming apparatus, in combination, a rectangular support having a flat top surface, an L-shaped abutment having one portion extending across one end portion of said surface and the other portion substantially parallel to the longitudinal edge of said support, and a spring clip secured to said support substantially adjacent said abutment and having its free end substantially parallel to said surface of said support. 15
12. In bow forming apparatus, in combination, a rectangular support having a flat top surface, an L-shaped abutment having one portion extending across one end portion of said surface and the other portion substantially parallel to the longitudinal edge of said support, and a spring clip secured to said support substantially adjacent said abutment and having its free end substantially parallel to said surface of said support, the end of said spring clip being up- 20 turned.
13. In bow forming apparatus, in combination, a rectangular support having a flat top surface, an L-shaped abutment having one portion extending across one end portion of said surface 25 and the other portion substantially parallel to the longitudinal edge of said support, and a spring clip secured to said support substantially adjacent said abutment and having its free end substantially parallel to said surface of said support, the end of the last-mentioned portion of 30 said abutment being beveled.
14. In bow forming apparatus, in combination, a rectangular support having a flat top surface, an L-shaped abutment having one portion extending across one end portion of said surface and the other portion substantially parallel to the longitudinal edge of said support, and a spring clip secured to said support substantially adjacent said abutment and having its free end 35 substantially parallel to said surface of said support, said spring clip running in a direction at right angles to the first-mentioned portion of said abutment and parallel to said second-mentioned portion of said abutment. 40
15. In bow forming apparatus, in combination, a rectangular support having a flat top surface, an L-shaped abutment having one portion extending across one end portion of said surface and the other portion substantially parallel to the longitudinal edge of said support, and a pair 45 of spring clips secured to said support at spaced points substantially adjacent the first-mentioned portion of said abutment, the free ends of said clips running substantially parallel to 50 said surface of said support. 55

RALPH K. REYNOLDS.
